UNITED STATES PATENT OFFICE.

ARTHUR CHAS. BROWN, OF NEWARK, NEW JERSEY, ASSIGNOR TO KREMENTZ & CO., OF NEWARK, NEW JERSEY, A PARTNERSHIP.

DESIGN FOR A BROOCH-PIN.

52,780.

Specification for Design.

Patented Dec. 24, 1918.

Application filed September 5, 1918. Serial No. 252,787. Term of patent 3½ years.

To all whom it may concern:

Be it known that I, ARTHUR CHAS. BROWN, a citizen of the United States, residing at No. 885 S. 15th St., city of Newark, county of Essex, State of New Jersey, have invented a new, original, and ornamental Design for a Brooch-Pin, of which the following is a specification, reference being had to

the accompanying drawing, forming part thereof.

The figure is a plan view of a brooch pin, showing my new design.

I claim—

The ornamental design for a brooch pin as shown.

ARTHUR CHAS. BROWN.
